UNITED STATES PATENT OFFICE.

TRUMAN D. WILBUR, OF BROCTON, NEW YORK.

DESIGN FOR A TOY ANIMAL.

Application filed October 7, 1922. Serial No. 3,900. Term of patent 3½ years.

To all whom it may concern:

Be it known that I, TRUMAN D. WILBUR, a citizen of the United States, residing at Brocton, in the county of Chautauqua and State of New York, have invented a new, original, and ornamental Design for a Toy Animal, of which the following is a specification, reference being had to the accompanying drawing, forming part thereof.

The figure in the drawing is a perspective view of a toy animal showing my new design.

I claim:

The ornamental design for a toy animal, as shown.

TRUMAN D. WILBUR.
